CHAISE LONGUE

Marcel G. Bretos, 140 E. 28th St.,
New York, N.Y. 10016

Filed Aug. 24, 1972, Ser. No. 283,597

Term of patent 14 years

Int. Cl. D6—01

U.S. Cl. D6—38

FIG. 1 is a side elevational view of a chaise longue showing my new design;

FIG. 2 is a top view; and

FIG. 3 is a front elevational view.

I claim:

The ornamental design for a chaise longue, substantially as shown.
